UNITED STATES PATENT OFFICE

2,107,622

FUEL DISTRIBUTING MECHANISM

Howard P. Anderson, Erie, Pa., assignor to The Standard Stoker Company, Inc., a corporation of Delaware

Application April 14, 1934, Serial No. 720,546

23 Claims. (Cl. 110—101)

This invention relates generally to stokers of the type that discharges fuel in aerial paths over the firebox, and has for its main object the provision of new and improved means for distributing the fuel over the firebed.

It is a more specific object of the invention to provide a compact, flexible fuel distributing mechanism for a stoker that is conveniently adjusted, without dismantling any part of the stoker or interrupting its operation, to distribute fuel in an even bed over the firebox under all conditions of firing.

A further object of the invention resides in the provision of novel distributing mechanism wherein fuel may be continuously spread in a uniform blanket over the entire firebed by a primary fuel distributing means and more or less fuel may be distributed over one side or the other of the firebed by auxiliary means independently of the primary distributing means.

Another object of the invention resides in the provision of a novel blast chamber member.

Other objects of the invention reside in the provision in a stoker of novel adjustable features that cooperate and are so related as to effect new and useful results.

With the above and other objects and advantages in view, the invention consists in the features of construction, the combination of elements and arrangement of parts hereinafter more fully described and claimed.

In the drawings,

Fig. 1 is a view in vertical longitudinal section of a portion of a locomotive with a portion of a stoker embracing the invention applied thereto and shown in elevation;

Fig. 2 is a sectional view taken on the line 2—2 of Fig. 1;

Fig. 3 is a sectional view taken on the line 3—3 of Fig. 2, with parts removed and shown in section;

Fig. 4 is a vertical sectional view on the line 4—4 of Fig. 2, with parts shown in elevation;

Fig. 5 is a fragmentary sectional view on the line 5—5 of Fig. 3;

Fig. 6 is a sectional view taken on the line 6—6 of Fig. 3;

Fig. 7 is a sectional view taken on the line 7—7 of Fig. 3;

Fig. 8 is an enlarged fragmentary view in vertical longitudinal cross section of the distributor head;

Fig. 9 is a sectional view on the line 9—9 of Fig. 8;

Fig. 10 is a view similar to the view shown in Fig. 7 of a modified form of the invention;

Fig. 11 is an isometric view of a plate-like member which forms a portion of the front wall of the stoker conduit; and

Fig. 12 is a sectional view on the line 12—12 of Fig. 6.

The invention is particularly adapted to stokers for use with locomotives and is so illustrated and described. It will be obvious, however, that the invention is not so limited and may be applied to stockers for other furnaces where like conditions prevail.

In the drawings, the locomotive is designated generally by the numeral 10 and is provided with a main supporting frame 11 and a firebox 12. The firebox 12 is provided with grates 13, a smoke arch 14 supported on the customary arch tubes 15 and a backwall 16 having a firing opening 17 therethrough. Flues 18 extend forwardly from the flue sheet 19 at the forward end of the firebox 12. A suitable stoker, indicated as a whole at 20, is provided for conveying the fuel from a source of supply and delivering it to the firing opening 17. The part of the stoker mechanism illustrated comprises a riser casing 21, which is at the forward end of a series of conduit elements leading from a source of supply, such as the tender of a locomotive. One of this series of conduit elements is shown at 22 and a conveyor screw for advancing fuel therethrough is shown at 23.

A housing 24 surmounts the riser casing 21 and communicates with the firing opening 17. The housing 24 is apertured opposite the firing opening as at 25, through which aperture access may be gained to the firebox and through which fuel may be hand fired. A firedoor 26, of any suitable type, is arranged to form a closure for the aperture 25.

As the fuel emerges from the riser casing 21 into the housing 24 it is projected forwardly through the firing opening 17 into the firebox by a pressure fluid blast issuing from the blast chamber casting 27, which casting is mounted in the rear wall of the riser casing 21 at the rear of the rising column of fuel. The blast chamber casting 27 comprises a plate-like portion 28, overlapping the inner marginal edges of an opening 29 in the rear wall of the casing 21, and a hub portion 30 passing freely through the opening 29. A cover plate 31 is mounted on the hub portion 30 and is drawn up tightly against the shoulder 32 by screwing the valve body 33 on the threaded portion 34 of the hub 30. The outer portion of 55

the cover plate 31 overlaps the outer marginal edge of the opening in the rear wall of the casing 21, thereby holding the blast chamber casting 27 in contact with the rear wall of the casing 21, yet permitting sliding movement of the casting 27 along the rear wall of the casing 21 to any desired position, limited only by the clearance between the hub 30 and the marginal edge of the opening 29.

10 Adjustment of the blast chamber casting 27 in a horizontal transverse path is effected by an adjusting screw 35. This screw 35 is threaded through a boss 35a and carries a head 36 received in the guide member 37 of the blast chamber casting 27. Now, when the screw 35 is turned in one direction, the head 36 exerts pressure against the wall 38 moving the blast chamber casting 27 horizontally in one direction; and when the screw is turned in the opposite direction, the head 36

15 exerts pressure against the slotted wall 39 moving the blast chamber casting horizontally in the opposite direction. The wall 39 is slotted vertically and the guideway for the head 36 extends vertically through the guide member 37 so that the blast chamber casting may be adjusted vertically.

20

Vertical adjustment of the blast chamber casting 27 is provided for by a pair of adjusting screws 40, each of which has a right-hand thread threaded in the flange 41 of the casing 21 and a left-hand thread threaded in a block 42 which is arranged to slide horizontally in a groove 43 in the valve body 33. Vice versa, the left-hand threads may be threaded in the flange 41 and the right-hand threads may be threaded in the block 42.

occurs when uneven draft conditions cause the fuel to burn through more rapidly on one side of the firebox than the other, it is necessary, with the present device, only to turn the adjusting wheel 79 in a direction to cause one of the jet openings in the jet pipe 72 to be blanked off and the other to be directed toward the side of the firebox to which it is desired to deliver more fuel. Thus, while an even blanket of fuel continues to be spread over the entire firebox by the primary blast or jets 62, the jet pipe 72 is spreading another blanket of fuel over that side of the firebox to which it is desired to deliver more fuel. When the temporary uneven condition of the firebed has been corrected, it is necessary only to manipulate the hand wheel 79 to turn the jet pipe 72 to its original position. No adjustment or regulation of the primary distributing jets 62 is required.

When the greater demand for fuel on one side of the firebox than the other, due to uneven draft conditions or for some other reason, is of a more permanent nature, mere adjustment of the jet pipe 72 is not sufficient, and an arrangement hereinafter described is provided to correct such conditions. The upper portion of the front wall 63 of the casing 21 is formed by a separable plate-like member 80 which overlaps and is secured at its lower end to the upper outer side of the lower portion of the front wall 63 and along its sides is secured to the ledges 81 extending inwardly of the side walls of the casing 21. The inner surface of the plate-like member 80 has a raised portion 82 extending centrally and longitudinally thereof and projecting above its upper edge to form a ridge 83 that extends above the level of the distributor plate 64 but terminates below the level of the jets 62. A pair of plates 84 and 85, one at each side of the raised portion 82, are arranged to slide vertically in the races 86 and 87 formed respectively by the lips 88 and 89 and the surface of the plate-like member 80. The plates 84 and 85 may be independently adjusted to any desired height by turning the hand wheels 90 and 91, respectively. The hand wheels 90 and 91 are threaded on the threaded stems 92 and 93, respectively, which in turn are attached to the bars 94 and 95, respectively, mounted to slide in a horizontal transverse path in the slot 96 formed in the lower portion of the plate-like member 80. The bars 94 and 95 are provided with pins 97 and 98, respectively, which engage the diagonal slots 99 and 100, respectively, formed in the lower portion of the plates 84 and 85, respectively.

Now, if it is desired to project a greater quantity of fuel to one side of the firebox, for example the right side, the plate on that side is raised to a point where substantially all of the fuel must come within the zone of action of the blast issuing from the jets 62 and be projected thereby. At the same time, the plate on the opposite side is lowered so that a considerable portion of fuel will fall thereover onto the plate 64 and a limited amount only will enter the zone of action of the blast issuing from the jets 62. Thus, it will be apparent that more fuel is being projected into the firebox on the right side than on the left side. The quantity of fuel delivered to the left side of the firebox may be still further limited by reducing the pressure in the jets 62 on the left side whereby the blast issuing therefrom will project the fuel onto the plate 64 instead of directly into the firebox. The jet pipe 72 may be adjusted to project the fuel that collects on the plate

64 to the right side of the firebox or to other desired portions thereof.

The jets 62 take care of distribution of fuel to all parts of the firebox except the rear corners. Since the jets 62 are a distance rearward of the firing opening and cannot be directed towards the rear corners of the firebox, a top deflector, indicated as a whole by the numeral 101, is provided to serve those areas of the firebox. The top deflector 101 includes a pair of deflecting members 102 and 103 disposed above the plate 64, one at each side of the firing opening. Each of the deflecting members 102 and 103 comprises an elongated bar 104 and a flattened horizontal blade portion 105 having a curvate forward edge 15 from which depends a curved skirt 106.

The deflecting members 102 and 103 are secured at their rearward ends to the shafts 107 and 108, respectively, mounted respectively in the blocks 109 and 110. Guideways 111 and 112 are formed in the opposite side walls of the housing 24 in which the blocks 109 and 110, respectively, are arranged to slide vertically. The shafts 107 and 108 are journaled in the blocks 109 and 110, respectively, and have threaded thereon the adjusting nuts 113 and 114, respectively, which when turned will move the deflecting members 102 and 103 horizontally closer or farther apart, as desired. Adjusting screws 115 and 116, threaded in the bosses 117 and 118, respectively, are arranged when turned to raise or lower the blocks 109 and 110, respectively, whereby independent vertical adjustment of the deflecting members 102 and 103 is effected. Angular adjustment in a vertical plane of the deflecting members 102 and 103 about their rearward ends is provided for by the arms 119 and 120, which are keyed to the shafts 107 and 108, respectively, and are turned by the hand wheels 121 and 122, respectively.

The deflecting members 102 and 103 are provided with curved plates 123 and 124, respectively, converging as they extend rearwardly from the inner edges of the skirts 106. The plates 123 and 124 together with the skirts 106 serve to intercept a portion of the projected fuel and direct it to the rear corners of the firebox. The independent adjustability of the deflecting members permits the delivery of more or less fuel to one of the rear corners of the firebox independently of the other rear corner and the quantity of fuel delivered to either corner is conveniently controlled by the vertical, horizontal and angular adjustment of the deflectors.

A top plate 125 supported by the deflecting members 102 and 103 extends rearwardly from the skirts 106 over the curving plates 123 and 124 and is split longitudinally into overlapping sections 126 and 127 to permit the independent adjustment of the deflecting members. The top plate 125 prevents the blast from spreading in an upward direction, thereby minimizing the amount of fine fuel particles that otherwise would be carried over the arch of the firebox and escape through the stack unconsumed.

The blast chamber casting 28 is provided with a splitter plate 128, comprising a horizontal row of preferably tetrahedrally shaped teeth 129 subjacent the openings 54. When wet fuel is being fed, the splitter plate 128 is particularly advantageous, since it breaks up the coherent mass of fuel tending to spread the fuel out in front of the pressure fluid blast issuing from the jets 62.

In Fig. 10 is shown a modified form of means for projecting the fuel from the distributor plate. 75

In place of the single jet pipe 72, casing 74 and adjustable operating means therefor, best shown in Fig. 7 of the preferred form of the invention, a pair of jet pipes 130 and 131, each provided with a single jet opening, 132 and 133, respectively, and each enclosed by a stationary casing 134 and 135, is provided. The jet pipes 130 and 131 are independently operated by means described in connection with the preferred form 10 of the invention, which need not be repeated.

From the foregoing description, it will be apparent that I have provided a compact, extremely flexible fuel distributing mechanism for stokers that is conveniently adjusted from within 15 cut the stoker, without dismantling any part of the stoker or disturbing its operation, to distribute fuel evenly over the firebox under any and all conditions of draft, kind and condition of fuel used and other conditions of firing.

20 I claim:

1. In a mechanical stoker, the combination of a firebox having a wall with a firing opening therein, a conduit for delivering fuel to said firing opening, a pressure fluid distributor head 25 movably mounted on the rear wall of said conduit opposite the lower portion of said firing opening and means for adjusting said distributor head to any one of a number of positions vertically and horizontally along said conduit rear wall, said distributor head being provided with jet openings directed toward said firing opening.

2. In a mechanical stoker, the combination of a firebox having a wall with a firing opening therein, a conduit for delivering fuel to said firing opening, a pressure fluid distributor head 35 movably mounted on the rear wall of said conduit opposite the lower portion of said firing opening, said head being provided with discharge openings, means for adjusting said distributor head to any one of a number of positions vertically and horizontally along said conduit rear wall, a jet casting rotatively mounted in said distributor head, said jet casting being provided with jet passages directed through the discharge openings in said distributor head and toward the firing opening and means for rotating said jet casting to adjust said jet passages to any one of a number of positions angularly with respect to the horizontal.

3. In a mechanical stoker, the combination of a firebox having a wall with a firing opening therein, a conduit for delivering fuel to said firing opening, a pressure fluid distributor head 50 movably mounted on the rear wall of said conduit opposite the lower portion of said firing opening, means for adjusting said distributor head to any one of a number of positions vertically and horizontally along said conduit rear wall, said head being provided with jet openings directed toward the firing opening and a splitter plate extending transversely thereof subjacent said jet openings.

4. In a mechanical stoker, the combination of a firebox having a wall with a firing opening therein, a fuel feed device communicating with 55 said firing opening, a pressure fluid distributor head movably mounted on the rear wall of said fuel feed device, means for adjusting said distributor head to any one of a number of positions vertically and horizontally along said rear wall, jet openings in said distributor head for the emission of pressure fluid for projecting fuel through the firing opening into the firebox, and a pair of spaced deflecting members mounted 60 each on a respective side wall of said fuel feed

device, said deflecting members being arranged to intercept a portion of the projected fuel and to divert such portions to the rear corners of the firebox.

5. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said rear wall, jet openings in said distributor head for the emission of pressure fluid for projecting fuel through the firing opening into the firebox, a 15 pair of spaced deflecting members, each vertically movably mounted on a respective side wall of said fuel feed device, and means for adjusting said deflecting members vertically to any one of a number of positions independently of each other, said deflecting members being arranged to intercept a portion of the projected fuel and to divert such portions of the rear corners of the firebox.

6. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said rear wall, jet openings in said distributor head for the emission of pressure fluid for projecting fuel through the firing opening into the firebox, a 30 pair of spaced deflecting members, each mounted on a respective side wall of said fuel feed device for horizontal transverse adjustment, and means for adjusting said deflecting members horizontally and transversely to any one of a number of positions independently of each other, said deflecting members being arranged to intercept a portion of the projected fuel and to divert such portions to the rear corners of the firebox.

7. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said rear wall, jet openings in said distributor head for the emission of pressure fluid for projecting fuel through the firing opening into the firebox, a 45 pair of spaced deflecting members, each mounted for vertically swinging adjustment about its rearward end on a respective side wall of said fuel feed device, and means for adjusting said deflecting members to any one of a number of positions angularly with respect to a horizontal plane independently of each other, said deflecting members being arranged to intercept a portion of the projected fuel and to divert such portions to the rear corners of the firebox.

8. In a mechanical stoker, the combination of a firebox having a wall with a firing opening therein, a fuel feed device communicating with said firing opening, a pressure fluid distributor head mounted on the rear wall of said fuel feed device arranged to project fuel into the firebox, a distributor plate in said firing opening below the zone of action of said distributor head arranged to receive fuel from said fuel feed device, means comprising a substantially vertically a 1- 75

justable plate at the rear of said distributor plate for proportioning the amount of fuel delivered respectively into the zone of action of said distributor head and onto said distributor plate and means for projecting the fuel from said distributor plate to predetermined areas of the firebox independently of said pressure fluid distributor head.

9. In a mechanical stoker, the combination of a firebox having a wall with a firing opening therein, a fuel feed device communicating with said firing opening, a pressure fluid distributor head mounted on the rear wall of said fuel feed device arranged to project fuel into the firebox, a distributor plate in said firing opening below the zone of action of said distributor head arranged to receive fuel from said fuel feed device, means, comprising a pair of transversely extending plates at the rear of said distributor plate and means for independently adjusting the vertical extent of said plates above the level of said distributor plate, for proportioning the amount of fuel delivered respectively into the zone of action of said distributor head and onto said distributor plate and means for projecting the fuel from said distributor plate to predetermined areas of the firebox independently of said pressure fluid distributor head.

10. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said fuel feed device rear wall, said head being provided with jet openings for the emission of pressure fluid blast for projecting fuel through the firing opening into the firebox, top deflecting means arranged to cooperate with said pressure fluid blast to distribute fuel over the entire firebox, a distributor plate in said firing opening below the level of said pressure fluid blast, the front wall of said fuel feed device extending above the level of said distributor plate but terminating below the level of the zone of action of said pressure fluid blast whereby a portion of the fuel will spill onto said distributor plate, and means for projecting the fuel spilling onto said plate into the firebox.

11. In a mechanical stoker, the combination of a firebox having a wall with a firing opening therein, a fuel feed device communicating with said firing opening, a pressure fluid distributor head movably mounted on the rear wall of said fuel feed device arranged to project fuel into the firebox, means for adjusting said distributor head to any one of a number of positions vertically and horizontally along said fuel feed device rear wall, a distributor plate in said firing opening below the zone of action of said distributor head arranged to receive fuel from said fuel feed device, means for angularly adjusting said distributor plate vertically about a transverse axis at its rearward end and means for projecting the fuel from said plate to predetermined areas of the firebox independently of said pressure fluid distributor head.

12. In a mechanical stoker, the combination of a firebox having a wall with a firing opening therein, a fuel feed device communicating with said firing opening, a pressure fluid distributor head mounted on the rear wall of said fuel feed device arranged to project fuel into the firebox,

a distributor plate in said firing opening below the zone of action of said distributor head arranged to receive fuel from said fuel feed device, said distributor plate being pivotally mounted at its rearward end on a transverse, horizontal axis, means for adjusting said distributor plate to any one of a number of positions angularly with respect to the horizontal, means comprising a substantially vertically adjustable plate at the rear of said distributor plate for proportioning the amounts of fuel delivered respectively into the zone of action of said distributor head and onto said distributor plate and means for projecting the fuel from said distributor plate to predetermined areas of the firebox independently of said pressure fluid distributor head.

13. In a mechanical stoker, the combination of a firebox having a wall with a firing opening therein, a fuel feed device communicating with said firing opening, a pressure fluid distributor head movably mounted on the rear wall of said fuel feed device arranged to project fuel into the firebox, means for adjusting said distributor head to any one of a number of positions vertically and horizontally along said conduit rear wall, a distributor plate in said firing opening below the zone of action of said distributor head arranged to receive fuel from said fuel feed device and means for projecting the fuel from said plate to predetermined areas of the firebox independently of said pressure fluid distributor head.

14. In a mechanical stoker, the combination of a firebox having a wall with a firing opening therein, a fuel feed device communicating with said firing opening, a pressure fluid distributor head for projecting fuel into the firebox mounted on the rear wall of said fuel feed device, a pair of spaced fuel deflecting members mounted each on a respective side wall of said fuel feed device, means for moving said deflecting members in a vertical direction, means for moving said members in a horizontal transverse direction and means for moving said members pivotally about a transverse axis at their rearward ends whereby said deflecting members may be adjusted to any one of a number of positions to intercept portions of the projected fuel and to divert such portions to the rear corners of the firebox, a distributor plate in said firing opening below the zone of action of said distributor head arranged to receive fuel from said fuel feed device and means for projecting the fuel from said plate independently of said pressure fluid distributor head.

15. In a mechanical stoker, the combination of a firebox having a wall with a firing opening therein, a fuel feed device communicating with said firing opening, a pressure fluid distributor head for projecting fuel into the firebox mounted on the rear wall of said fuel feed device, a pair of spaced fuel deflecting members mounted each on a respective side wall of said fuel feed device, means for moving said deflecting members in a vertical direction, means for moving said members in a horizontal transverse direction and means for moving said members pivotally about a transverse axis at their rearward ends whereby said deflecting members may be adjusted to any one of a number of positions to intercept portions of the projected fuel and to divert such portions to the rear corners of the firebox, a distributor plate in said firing opening below the zone of action of said distributor head arranged to receive fuel from said fuel feed device, means comprising a substantially vertically adjustable plate at the rear of said distributor plate for proportioning

the amount of fuel delivered respectively into the zone of action of said distributor head and onto said distributor plate and means for projecting the fuel from said distributor plate to predetermined areas of the firebox independently of said pressure fluid distributor head.

16. In a mechanical stoker, the combination of a firebox having a wall with a firing opening therein, a conduit for delivering fuel to said firing opening, a pressure fluid distributor head movably mounted on the rear wall of said conduit opposite the lower portion of said firing opening, means for adjusting said distributor head to any one of a number of positions vertically and horizontally along said conduit rear wall, said head being provided with jet openings directed toward the firing opening and a splitter plate movable with said head and extending transversely thereof subjacent said jet openings, said splitter plate comprising a horizontal row of tetrahedrally shaped teeth projecting inwardly of the conduit.

17. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said rear wall, jet openings in said distributor for the emission of pressure fluid for projecting fuel through the firing opening into the firebox, a pair of spaced deflecting members mounted each on a respective side wall of said fuel feed device, said deflecting members being arranged to intercept portions of the projected fuel and to divert such portions to the rear corners of the firebox and a longitudinally split top plate supported on said deflecting members.

40 18. In a mechanical stoker, the combination of a firebox having a wall with a firing opening therein, a fuel feed device communicating with said firing opening, a pressure fluid distributor head mounted on the rear wall of said fuel feed device for projecting fuel to all parts of the firebox except the rear corners thereof, a pair of spaced deflecting members mounted each on a respective side wall of said fuel feed device, said deflecting members being arranged to intercept portions of the projected fuel and to divert such portions to the rear corners of the firebox, a distributor plate in said firing opening below the zone of action of said distributor head arranged to receive fuel from said fuel feed device and means for projecting the fuel from said plate to predetermined areas of the firebox independently of said pressure fluid distributor head.

60 19. In a mechanical stoker, the combination of a firebox having a wall with a firing opening therein, a conduit for delivering fuel to said firing opening, the rear wall of said conduit being provided with an aperture opposite the lower portion of the firing opening, a pressure fluid distributor head mounted on said rear wall overlapping the inner marginal edges of the conduit that define said aperture, said pressure fluid head having a hub passing freely through said aperture and spaced on all sides from the margin thereof, means cooperating with said hub for drawing said pressure fluid distributor head against said conduit wall, and means for adjusting said distributor head in any one of a number of positions limited by the clearance between

said hub and the edges of the conduit that define said aperture.

20. In a mechanical stoker, the combination of a firebox having a wall with a firing opening therein, a conduit for delivering fuel to said firing opening, a pressure fluid distributor head provided with discharge openings, said head being movably mounted on the rear wall of said conduit opposite the lower portion of said firing opening, said head being provided with a splitter plate extending transversely thereof and comprising a horizontal row of tetra-hedrally shaped teeth projecting inwardly of the conduit, means for adjusting said distributor head to any one of a number of positions vertically and horizontally along said conduit rear wall, a transversely extending jet casting rotatively mounted in said distributor head, said jet casting being provided with jet passages communicating with the discharge openings in said distributor head, and means for rotating said jet casting to adjust said jet passages to any one of a number of positions angularly with respect to the horizontal.

21. In a mechanical stoker, the combination of a firebox having a wall with a firing opening therein, a fuel feed device communicating with said firing opening, a pressure fluid distributor head movably mounted on the rear wall of said fuel feed device, means for adjusting said distributor head to any one of a number of positions vertically and horizontally along said rear wall, jet openings in said distributor head for the emission of pressure fluid for projecting fuel through the firing opening into the firebox, a pair of spaced deflecting members, each mounted at a respective side of said fuel feed device, means for adjusting said deflecting members vertically to any one of a number of positions, means for adjusting said deflecting members horizontally and transversely to any one of a number of positions, and means for adjusting said deflecting members vertically about their rearward ends to any one of a number of positions angularly with respect to a horizontal plane, said deflecting members being arranged to intercept portions of the projected fuel and to divert such portions to the rear corners of the firebox.

22. In a mechanical stoker, the combination of a firebox having a wall with a firing opening therein, a fuel feed device communicating with said firing opening, a pressure fluid distributor head movably mounted on the rear wall of said fuel feed device opposite the lower portion of said firing opening, means for adjusting said distributor head to any one of a number of positions vertically and horizontally along said rear wall, said distributor head being provided with jet openings directed toward said firing opening, a distributor plate in said firing opening below the zone of action of said distributor head arranged to receive fuel from said fuel feed device, means comprising a pair of transversely extending plates at the rear of said distributor plate and means for independently adjusting the vertical extent of said plates above the level of said distributor plate, for proportioning the amount of fuel delivered respectively into the zone of action of said distributor head and onto said distributor plate, and means for projecting the fuel from said distributor plate to predetermined areas of the firebox independently of said pressure fluid distributor head.

23. In a mechanical stoker, the combination

of a firebox having a wall with a firing opening therein, a fuel feed device communicating with said firing opening, a pressure fluid distributor head movably mounted on the rear wall of said 5 fuel feed device, said distributor head being provided with discharge openings, means for adjusting said distributor head to any one of a number of positions vertically and horizontally along said rear wall, a jet casting rotatively 10 mounted in said distributor head, said jet casting being provided with jet passages directed through the discharge openings in said distributor head and toward the firing opening, means for rotating said jet casting to adjust said jet passages to any one of a number of positions angularly with respect to the horizontal and a pair 5 of spaced deflecting members mounted each on a respective side wall of said fuel feed device, said deflecting members being arranged to intercept portions of the projected fuel and to divert such portions to the rear corners of the firebox. 10

HOWARD P. ANDERSON.
